UNITED STATES PATENT OFFICE

120,941

DESIGN FOR A BOTTLE COLLAR OR THE LIKE

Leroy P. Neher, St. Louis, Mo.

Application April 22, 1939, Serial No. 84,505

Term of patent 3½ years

To all whom it may concern:

Be it known that I, Leroy P. Neher, a citizen of the United States, residing in the city of St. Louis, State of Missouri, have invented a new, original, and ornamental Design for a Bottle Collar or the like, of which the following is a specification, reference being had to the accompanying drawing, forming a part thereof, in which:

Fig. 1 is a front elevation of the bottle collar or the like showing my new design;

Fig. 2 is a side elevation thereof; and,
Fig. 3 is a rear elevation thereof.

The dominant feature of the invention consists in the configuration of the upper edge in the manner shown.

I claim:

The ornamental design for a bottle collar or the like, as shown and described.

LEROY P. NEHER.
